NIBBLING MACHINE

Karl Gustaf Östberg, Stockholm, Sweden, assignor to Fabriksaktiebolaget Haldataxamtern, Holmstad, Sweden, a company of Sweden

Application July 16, 1936, Serial No. 90,989
In Sweden July 20, 1935

10 Claims. (Cl. 164—41)

The invention relates to a machine for working, especially shearing metal plates and other sheet material. It relates particularly to such machines in which the shearing is effected by cutting or stamping out a narrow strip from the plate. Machines of this kind are known, which consist substantially of a support for the metal plate in the shape of a stamping pad and of a stamp or punch movable up and down through a recess in said support, and in which the guiding means and the driving mechanism are arranged below the supporting surface for the plate. Such machines have the advantage of being free from any superstructure above the working table which would take up much room above the table and would bar the feeding of the plate to the stamp. On account of the great stresses to which the stamp and the motion mechanism are subjected in said type of machines it has, however, been difficult to find a suitable design for the stamp and the motion mechanism. The present invention has for its object to provide an improvement in this respect in machines of the kind mentioned and consists substantially therein that the stamp is swingably mounted in the support. It is hereby rendered possible to obtain a secure and reliable mounting and guiding of the stamp, and in addition the transmission of movement can be arranged in a more simple manner by means of rotating members only, resulting in a compact and reliable construction. For the transmission of movement there is preferably employed a so-called waddling disk which may be pivotally mounted in the working table proper immediately below the upper surface of the table and may be arranged to be driven from a shaft which is perpendicular to said surface.

The invention will be described more in detail with reference to the accompanying drawing, in which

Figure 1 shows a vertical section through a machine according to the invention.

Figure 2 shows a vertical section on the line 2—2 in Figure 1.

Figure 3 is a plan view of the machine.

Figures 4 and 5 show in side-view and plan view one half of the support on the working table according to a modified embodiment. Figures 6 and 7 show in side view and plan view respectively a stamping member corresponding thereto.

Figures 8 and 9 show in vertical section and plan view another embodiment of the machine. Figure 10 shows the cutting portion of the stamp in front view, and Figure 11 a section on the line 11—11 in Figure 8.

Figure 12 shows in a similar section another embodiment of the cutting portion of the stamp.

In the embodiment shown in Figures 1 to 3, the frame of the apparatus consists of a horizontal foot 1 provided with ears 2, 3 for clamping the frame to a suitable foundation a vertical portion 4, which forms part of a cylinder, and an upper horizontal portion 5 which supports the stamping pad or support for the plate. Said stamping pad is a substantially cylindrical body composed of two symmetrical parts 6, 7 inserted in a conical recess in the portion 5, said halves forming a plane supporting surface 8 for the metal plate. In said pad 6, 7 is provided a slit shaped recess 9 formed by milling the opposite sides of the two halves 6, 7. Disposed in said recess is the stamp 10 which consists of a disk having parallel side surfaces and which is swingably mounted on a pivot 11 which extends transversely of the slot and is formed by two extensions 12 of the halves 6, 7 which project towards each other. The pivot 11 is cut off along a plane coinciding with the supporting surface 8. The axis of said pivot may be positioned above or below the surface 8. The stamping disk 10 is provided with a bore 12 corresponding to the pivot 11 and with two guiding edges 13, 14 which are concentric with said bore and which, on movement of the stamp, slide along the corresponding cylindrical end surfaces in the slit 9. The stamp 10 has also two straight parallel edges 15, 16 one of which, 16, bears against the upper plane surface of a waddling disk 17 mounted in a conical recess 18 in the pad 6, 7. The waddling disk is provided with a shank 19, the lower button-shaped end 20 of which is received in an eccentric recess 21 in the end wall 22 of a pulley 23 which is journalled on a cylindrical extension 24 of the pad 6, 7 and which with its end wall 22 rests on an elevated portion 25 of the foot 1 of the frame. The convex surface of the waddling disk 17 is shaped as a truncated spherical calotte the centre of which is positioned in the extension of the axis of the waddling disk. On rotation of the pulley 23, the button-shaped end 20 of the shank 19 will perform a revolving movement, the longitudinal axis of the waddling disk then describing a revolving movement in the surface of a cone. The stamping disk 10 is arranged in such position that its swinging axis intersects the axis of the cone 50 traced by the axis of the waddling disk. Consequently, the stamping disk will perform a swinging movement about the pivot 11 in the plane of the guiding slit 9.

The stamping disk is provided with a cutting

portion in the shape of a tooth 26 formed by two notches 27, 28 in the periphery of the disk. The tooth has the same width as the slit 10. The portions 29, 30 of the stamping disk positioned behind the tooth are thinner than the rest of the disk in order that it shall be possible to feed the plate to the stamp without friction against the sides of the stamp.

When the machine is used, the plate is moved 10 on to the stamping disk along the plane upper surface 8 of the stamping pad. Since the stamping disk 10 is performing a rapid swinging movement, the plate will move in under the tooth 26 and a corresponding portion of the plate will be 15 stamped out each time the tooth moves in the direction towards the pad down into the slit 9. The cuttings drop into a recess or hollow 31 in the pad and pass from here out of the machine through a recess 32 in the frame portion 5. 20 When the cutting edges of the tooth have become worn, the pad can be readily taken apart and the stamping disk 10 turned round, so that the opposite side of the tooth becomes operative. When 25 the corresponding edges of the slit 9 become worn the stamping disk 10 can also be turned, so that the tooth will act in the diagrammatically opposite end of the slit 9. For said purpose similar recesses 33 and 34 are provided at the opposite side of the pad and frame respectively through 30 which the cuttings can leave the machine.

In order that the stamping disk 10 shall be securely guided in the slit 9 circular recesses 35 that are concentric with the pivot 11 may be provided in the opposite side surfaces of the parts 35 6, 7 as shown in Figures 4 and 5, the stamping disk being provided with a hub 36, Figures 6 and 7, fitting into said recesses. In the embodiment shown in Figures 6 and 7 the stamping disk is provided with an open slit at the end opposite 40 the tooth 26, and in addition the portion 29 immediately behind the tooth has a section which tapers towards the centre of the disk for the purpose of enabling shearing to be effected along lines having a comparatively small radius of curvature.

In the embodiment shown in Figures 8 and 9, those portions of the support or pad 6, 7 which are particularly subjected to wear are formed by detachable rings and ring segments inserted in circular slots in the pad. There are thus provided two inner ring segments 37, 38, each of which is somewhat smaller than a semicircle in order to leave both ends of the slit 9 free, and also an outer ring 40 which is provided with an open slit at 39. 55 and embraces the two first mentioned ring segments. Said ring-shaped portions are placed in a slot provided in the pad 6, 7, which slot is limited on its outer side by the upper portion of the cylindrical frame 41, provided with open slits at 42 so that it can be slightly compressed. The ring-shaped parts 37, 38 and 40 are held in position by means of a ring 43 embracing the upper part of the frame 41, which ring is provided with an open slit at 44 and is adapted to be tightened around 60 the frame, by means of a screw bolt 45 so that the upper portion of the frame is compressed and clamps the ring-shaped parts 37, 38, 40 in position. The portions of said parts, which are subjected to wear, are the ends 46, 47 of the ring segments 70 37, 38 and the portion 48 of the ring 40 positioned right opposite the slit 9. Thanks to the described arrangement of the rings 37, 38, 40 said edge portions 46, 47, 48 can be easily renewed according as they are worn out. The outer ring 40 can 75 be successively turned, so that new sharp edge

portions get in position right opposite the slit 9. The ends of the ring segments 37, 38 may, when required, be ground off and thereafter fitted into position again at opposite sides of the slit. The ring-shaped parts 37, 38, 40 preferably consist of 5 hardened steel whereas the other portions of the pad 6, 7 may consist of bronze or steel.

Figures 8, 10 and 11 show the cutting portion 49 of the stamp and the supporting edge 50 positioned therebelow which in this embodiment is 10 somewhat pointed or bulged out on its fore side so as to provide space for the expansion of the cuttings at opposite sides of the middle portion of the supporting edge. However, the supporting edge can also be given another cross-sectional 15 shape. The front side can thus be straight, as shown in Figure 12. The cutting portion 49 of the stamp can, if desired, also consist of a replaceable member of hardened steel.

In the embodiment shown in Figures 8 and 9 20 the frame 41 is assumed to consist of a cylindrical body, the driving means then consisting preferably of an electric motor mounted within the frame with its shaft perpendicular to the upper surface 8 of the stamp.

I claim:—

1. A nibbling machine comprising a stamping pad the upper surface of which forms the supporting surface for the plate to be cut, a slit-shaped recess in said stamping pad, a stamp 30 swingably mounted within said recess, a bearing for said stamp having its axis located in close proximity to said supporting surface and comprising concentric segmental sliding surfaces arranged below said surface, a pad supporting 35 frame, a motor for driving the stamp, and a motion mechanism for imparting a swinging motion to the stamp, said motion mechanism being mounted in said frame below the stamping pad.

2. A nibbling machine comprising a stamping 40 pad the upper surface of which forms the supporting surface for the plate to be cut, a slit-shaped recess in said stamping pad, a stamp swingably mounted within said recess, a half-cylindrical pivot for said stamp disposed transversely of said recess and having its flat surface at a level with the upper surface of the stamping pad, a pad supporting frame, a motor for driving the stamp, and a motion mechanism for imparting a swinging motion to the stamp, said motion mechanism being mounted in said frame below the stamping pad.

3. A nibbling machine as claimed in claim 2, in which the stamping pad consists of two detachable symmetrical halves, the recess for the 55 stamp forming a space between the two halves.

4. A nibbling machine comprising a stamping pad the upper surface of which forms the supporting surface for the plate to be cut, a slit-shaped recess in said stamping pad, a stamp 60 swingably mounted within said recess, a pivot for said stamp disposed transversely of said recess close to the upper surface of the stamping pad, circular recesses in the pad, detachable ring-shaped parts placed in said circular recesses and 65 forming the cutting edges of the pad, a clamping ring embracing said ring-shaped parts so as to hold the latter firmly in place, a pad supporting frame, a motor for driving the stamp, and a motion mechanism for imparting a swinging motion 70 to the stamp, said motion mechanism being mounted in said frame below the stamping pad.

5. A nibbling machine as claimed in claim 4, in which the ring-shaped parts comprise two inner ring segments the opposite end portions of 75

which form the sides of the pad opening for the stamp, and an outer split ring the inner edge of which forms the outer side of said opening.

5 6. A nibbling machine as claimed in claim 4, in which the pad has a circular form and is clamped to the upper cylindrical portion of the frame by means of the clamping ring.

10 7. A nibbling machine comprising a stamping pad the upper surface of which forms the supporting surface for the plate to be cut, a slit-shaped recess in said stamping pad, a stamp swingably mounted within said recess, a pivot for said stamp disposed transversally of said recess close to the upper surface of the stamping pad, 15 a pad supporting frame, a motor for driving the stamp, and a motion mechanism for imparting a swinging motion to the stamp comprising a waddling disc adapted to be driven from a rotating shaft and mounted between a sliding edge of the stamp and a bearing surface of the pad so as to allow a sliding motion between the stamp and the waddling disc.

15 20 8. A nibbling machine as claimed in claim 7 in which the stamp is driven from a rotating shaft through the intermediary of a waddling disc the swinging axis of which is directed towards the swinging axis of the stamp.

9. A nibbling machine comprising a stamping pad the upper surface of which forms the supporting surface for the plate to be cut, a slit-shaped recess in said stamping pad, a pivot for 5 said stamp disposed transversally of said recess close to the upper surface of the stamping pad, a pad supporting frame, a motor for driving the stamp mounted in said frame below the stamping pad, and a motion mechanism for imparting a 10 swinging motion to the stamp comprising a waddling disc adapted to be driven from a rotating shaft and mounted between a sliding edge of the stamp and a bearing surface of the pad so as to allow a sliding motion between the stamp and the 15 waddling disc.

10 10. A nibbling machine as claimed in claim 9 in which the waddling disc is provided with a pivot the outer end of which engages a recess provided eccentrically in a rotating disc. 20

KARL GUSTAF ÖSTBERG.
